OWEN G. GILSTRAP, OF PORTLAND, OREGON

DISPATCHING AND RECEIVING HEAD AND WORKTABLE FOR PNEUMATIC SYSTEMS

Application filed October 13, 1930. Serial No. 488,428.

My invention is primarily intended for use in pneumatic transmission systems where carriers are to be employed in the transmission of change, sale slips, shop reports, articles of manufacture, and all places where the dispatching of such things is to be carried on by pneumatic transmission means.

It has been the custom in devices of this kind to provide a work table whereupon the dispatching inlets and receiving shoes are to be terminated and where the dispatching inlets and the receiving shoes are operated by a person on one side of the work table.

In my new and improved device the dispatching inlets and receiving shoes are installed upon the work table in single or double banks and so arranged that the operator may dispatch through to the other side from the cashier. The operator may also receive carriers from the receiving shoe located on the other side of the work table. Thus we can have twice the number of dispatching inlets within easy reach of the operator and also at rush periods they can place operators on both sides of the work table. In some systems where they are very busy it may be advisable to install upon the work table some of the dispatching inlets and receiving shoes in single bank so as not to condense the dispatchers and receivers too much.

In my new and improved device, the same is adapted for being manipulated by a single operator to operate pairs of heads at either side, so that a single operator may properly care for, transmit and receive, from either side of the work table, with equal facility.

The invention consists primarily of bifurcated transmitting and receiving heads which are in spaced relationship with each other, and which terminate centrally of a work table. The heads are arranged in pairs so that an operator may have easy access to the heads on either side of the work table.

A counter is provided at either side of the work table, with a foot rest being disposed at the bottom of the spaced legs and at either side thereof.

A diaphragm extends longitudinally of the table and extends from the receiving heads with a counter disposed at either side of the

diaphragm and with a change trough disposed between each of the counters and of the diaphragm.

The object of my invention is to provide a work table that may be used with equal facility from either side.

A further object of my invention consists in providing a double transmitting and receiving head that may be used with equal facility, from either side, and providing a work table separated by a longitudinal, vertical diaphragm, to divide the work table into two parts that may be used by dispatchers disposed at either side and to prevent the interchange of the commodities being handled from one side to the other, the purpose being, that during slack periods of work, one or more operators may be disposed at one side of the work table only, and during rush periods may be adapted for having operators disposed at either side, or both sides of the work table, with means being provided for the preventing of the commodities being received and dispatched, from being passed from one side to the other.

A further object of my invention consists in providing a simply constructed receiving and transmitting head system, being centralized upon a work table that may be used with equal facility from either side.

A still further object of my device consists in providing a work table for pneumatic systems that will afford the greatest comfort to the operators and that will facilitate their handling a maximum of pneumatic traffic with dispatch and at the same time render their respective acts, within their own working province.

With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

In the drawings:

Fig. 1 is a side elevation of one of my new and improved work tables shown in combina-

tion with a plurality of receiving and transmitting heads, of a pneumatic system.

Fig. 2 is a perspective, end view of the work table shown illustrated for the receiving and transmitting pneumatic heads.

Fig. 3 is a sectional, end view of the work table illustrated in Fig. 2.

Fig. 4 is an end view of the work table and a side view of the pneumatic heads terminating upon the table in pairs and from opposite directions.

Like reference characters refer to like parts throughout the several views.

I preferably form my device of a work table comprised of a plurality of legs 1, spaced apart by a diaphragm 2, that is disposed longitudinally of the work table and extends from the end legs entirely through the table. A supporting shelf 3 terminates the upper edge of the diaphragm. Counters 4 and 5 are disposed at either side of the work table with pockets 6 being disposed immediately below the counter into which supplies of various kinds to be handled by the operator are placed. The pockets are partitioned into desired length by separator blades 7 that are disposed therebetween. Change troughs 8 and 9 are disposed at either side of the counter and extend from the counter to the vertically disposed diaphragm. Money trays 10 are disposed within the money troughs with suitable pockets 11 being provided for receiving the change.

Pairs of pneumatic tubes 12, leading from the table are disposed upon the shelf 3 and pairs of transmitting tubes 13 are parallelly disposed to those of the receiving tubes 12, so that an operator disposed at either side of the work table may receive and transmit the carrier with equal facility within any, or all, of the receiving or transmitting tubes. Valves 14 are provided within the tubes with transmitting cylinder 15 being provided within the tube structure.

To afford greatest comfort to the users, foot rest bars 16 are supported within the leg structure of the table and are spaced apart, from the floor of the table and from the diaphragm, in order that the feet of the operator may rest directly upon the foot rest without contacting the floor or the central diaphragm.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow.

What I claim is:

1. In a device of the class described, the combination of a work table comprised of parallelly disposed legs spaced apart, a

diaphragm disposed centrally and longitudinally of the table structure, a supporting shelf superposed the diaphragm, counters disposed at either side of the diaphragm and spaced therefrom, change troughs disposed between the counters and the diaphragm, pockets disposed below the counters and money troughs and adapted for entry from the outside, batteries of pairs of transmission tubes and of receiving tubes arranged above the shelf, each of said pair of tubes being adapted for use from either side of the work table.

2. In a device of the class described, the combination of a work table comprised of legs separated by a diaphragm, counters and a shelf, the counters running longitudinally of the table and spaced apart from the diaphragm with money troughs disposed between the counters and the diaphragm, pockets disposed below the counters, pairs of transmission and receiving tubes superposed the shelf and arranged for dispatcher's use from either side of the table.

3. In a device of the class described, the combination of a work table having pairs of dispatching and receiving tubes arranged in spaced relation with each other and arranged longitudinally of the table, and each tube being adapted for being operated by a dispatcher from either side of the table.
